(57) **CLAIM**

The ornamental design for a pocket, as shown and described.

DESCRIPTION

FIG. 1 is a top, front, and left side perspective view of a pocket, showing my new design. The continuous S-shaped pattern shown in FIG. 1, and as used throughout FIGS. 2, 4, and 5, is meant to represent a loop fabric. The dotted pattern shown below the continuous S-shaped pattern in FIG. 1, and as used throughout FIGS. 2, 4, 5, and 7, is meant to represent a hook fabric, and is further meant to be different from the loop fabric described herein.

FIG. 2 is a front view of my new design.

FIG. 3 is a rear view of my new design. The continuous S-shaped pattern shown in FIG. 3, and as used throughout FIGS. 4-6, is meant to represent a loop fabric. The dotted pattern shown above the continuous S-shaped pattern in FIG. 3, and as used in FIG. 7, is meant to represent a hook fabric, and is further meant to be different from the loop fabric described herein.

FIG. 4 is a side view of my new design.

FIG. 5 is a side view of my new design.

FIG. 6 is a top view of my new design; and,

FIG. 7 is a bottom view of my new design.

The portions of the design shown in large broken lines are stitching and are part of the claimed design.
